PROCESS OF TREATING HYDROCARBON OILS

Ralph B. Pierce and Aubrey W. Trusty, Shreveport, La., assignors to Louisiana Oil Refining Corporation, Shreveport, La., a corporation of Virginia

Application August 27, 1929, Serial No. 388,688

1 Claim. (Cl. 196—28)

This invention relates to the treatment of hydrocarbon oils for the purpose of removing various sulphur compounds therefrom and purifying the oil. The invention is applicable to and covers the conversion and removal of various sulphur containing compounds, such as hydrogen sulphide, mercaptans, monosulphides and disulphides, for example. The invention as stated is applicable to hydrocarbon oils in general and 10 is especially suitable for topped and cracked naphthas from high sulphur bearing petroleum crudes, shale oils and products produced from the dry distillation of coal.

The use of the old time sulphuric acid method 15 for removing sulphur from oils is disadvantageous in that large losses are incurred as well as the removal of some of the valuable unsaturated compounds. These and other disadvantages are overcome by the present invention.

20 The cracked naphthas treated by the process of the present invention become more stable under the action of sunlight than naphthas treated by the sulphuric acid method. No neutral salts or esters are formed to give rise to acid properties 25 within the body of the treated oil when it is subjected to redistillation or to the action of sunlight.

The process can be carried out in such a way 30 that completely sweetened material may be obtained that does not require further chemical treatment.

The process can also be carried out in such a way 35 that incompletely sweetened material is obtained which will require only very small quantities of chemicals for final sweetening. This is due to the fact that sulphur compounds present in an untreated oil or in an acid treated oil can be decomposed or their chemical form so changed by this process with formation or libration of 40 hydrogen sulphide that the resultant deleterious compounds may be readily removed by present and accepted methods of removal.

In carrying out this invention the sulphur reducing material acts as a catalyst thereby enabling 45 extremely large amounts of oil to be treated with small amounts of the sulphur reducing material, thus reducing treating costs. The sulphur content of the hydrocarbon oil is reduced very materially by this process from its original sulphur content without the accompanying removal 50 of valuable hydrocarbon constituents.

It has been found that topped naphthas and 55 cracked naphthas treated by this process may be successfully blended to produce a stable gasoline whereas the two naphthas after acid treatment

often cannot be blended to produce a stable gasoline and will go badly off color.

The following is a description of the equipment, apparatus, design and method by which the invention may be carried out. It is to be understood, however, that the description is in no wise a limitation on other particular additions, changes or redesign which may be made to better handle the process in question, but is only described as a means of clearly indicating the particular method employed to obtain the desired results.

The process may be carried out with an arrangement of apparatus indicated somewhat diagrammatically in the accompanying drawing in which parts are shown in sectional elevation.

In the drawing, reference character 1 indicates a furnace that may be heated by means of fuel burners 2. The furnace is provided with a bridge wall 3 over the edge of which the hot products of combustion pass to a chamber 4 in which a heating coil 5 is located.

A supply tank 6 for the hydrocarbon oil to be desulphurized is located in such a position that a pipe 7 leads from it to a pump 8 from the outlet of which a pipe 9 leads to the heating coil 5 in the heating chamber 4.

A flue 10 extends from the lower portion of the chamber 4 into a vertically disposed gas flue 11 from the upper portion of which an outlet 12 leads 30 to a stack. The lower corner of the gas flue 11 may be filled with a filler 13, such as asbestos, for example, to aid in causing the hot gases to be appropriately distributed. A valved air inlet pipe 14 may be provided at the lower portion of the 35 gas flue 11, so that air may be admitted to cool or temper the hot gases, if desired. The flue 11 may be covered with heat insulating material 15.

A treating chamber or reaction chamber 16 is located in the flue 11, so that it will be heated 40 by the gases that enter through the flue 10. An inert carrier 17, such as steel wool, for example, is provided in the chamber 16 as a support for a catalyst that is used for treating the vapors of the hydrocarbon oil. Cadmium sulphide has been 45 found to be a suitable catalyst for the purpose of desulphurizing the hydrocarbon oils. The filler or support for the catalyst is packed loosely in the chamber 16 and is thoroughly impregnated with the catalyst, so that the vapors come into 50 intimate contact with the catalyst and channeling of the vapors through the chamber does not take place. A pipe 18 for the vapors leads from the heating coil 5 into the bottom of the chamber 16 and an outlet 19 is provided at the top 55

of the chamber 16 for the treated vapors. Thermometers or thermostats 20 may be provided at different elevations in the annular space between the chamber 16 and flue 11 to indicate the temperature and similar temperature indicating devices 21 may be provided in the chamber 16.

In operating the device the oil to be treated is pumped from the tank 6 through the heating coil 5 to vaporize the oil. The hot gases from the furnace 1, after heating the coil 5, pass through the flue 10 into the flue 11 and heat the chamber 16, the temperature being controlled, if necessary, by admitting the desired amount of air through the inlet pipe 14. The temperature in the chamber 16 may range from 250° F. to 700° F., the temperature from about 600° F. to 700° F. having been found so far to be most satisfactory. The oil vapors pass through the pipe 18 into the treating chamber 16 where they come into contact with the cadmium sulphide and the treated vapors pass through the outlet 19 into a condenser (not shown). The condensates from the treated oil may be washed with a weak solution of sodium hydroxide to remove the hydrogen sulphide.

The treatment of hydrocarbon oils containing sulphur compounds, as described above, has been found to convert the malodorous and corrosive sulphur compounds to sweet and non-corrosive compounds with practically no loss of the oil and with very little, if any, effect upon the unsaturated compounds in the oil. In case the

treated material is not completely sweetened, it can be more easily and cheaply doctor sweetened than untreated oils and has none of the neutral alkyl esters that are found in oils which had been treated by sulphuric acid method. The oil is also very stable to sunlight, and in view of the fact that the valuable unsaturated compounds are not removed, the material appears to have better anti-knock value.

Cadmium sulphide appears to act as a catalyst 10 and is especially useful for decomposing mercaptans, sulphides, and disulphides with the formation of hydrogen sulphide.

We claim:

The process of refining cracked petroleum 15 naphtha to decompose organic sulphur compounds present therein without polymerizing or otherwise destroying a substantial proportion of the unsaturated hydrocarbons of the naphtha, which comprises passing the cracked naphtha in 20 a confined stream through a heating zone in which the naphtha is vaporized, passing the resulting vapors through a contact zone in intimate contact with a steel wool carrier material impregnated with a cadmium sulphide catalyst, 25 maintaining a controlled temperature of from 600 to 700° F. in said contact zone, condensing the treated naphtha vapors from said contact zone, and washing the resulting condensate with an alkali solution to remove any hydrogen sulphide 30 contained therein.
